WATER CLOSET PAN

Filed June 20, 1929

FIG. 1.

FIG. 2.

Inventor:

Max Hollenweger

by

Ferdinand

Atty.

UNITED STATES PATENT OFFICE

MAX HOLLENWEGER, OF BONN, GERMANY

WATER-CLOSET PAN

Application filed June 20, 1929, Serial No. 372,513, and in Germany May 6, 1929.

In order to prevent the stoppage at the entrance to the siphon-like discharging channel of a water closet pan this portion has hitherto been considerably narrowed and consequently the admission cross-section is narrower than the discharge cross-section. Such a formation of channel results in stoppage, retards or hinders the carrying off of the solid matter like a shut-off valve. These constructions also possess the disadvantage that the quantity of water necessary to obtain the suction effect cannot enter the discharging channel.

These objections are overcome according to the invention in that a chamber is provided in front of the entrance to the siphon-like discharging channel of a water closet pan, the feature of which fore chamber consists in that it is provided with an inlet and outlet slot, the inlet slot in the fore chamber being perpendicular to the outlet slot.

An embodiment of the invention is illustrated by way of example in the accompanying drawing in which:

Fig. 1 shows a longitudinal section through the water closet pan.

Fig. 2 is a cross-section on line 2—2 of Fig. 1.

A fore chamber *c* of rectangular or other suitable cross-section, arranged between the pan *a* and the siphon channel *b*, serves for receiving the fecals. A slot *e*, the dimensions of which are the same as the cross-section of the fore chamber extends through the bottom *d* and through the wall *h* of the chamber *c* but perpendicular to the chamber *c*. The fore chamber serves as mouth of the siphon channel *b*. The siphon channel up to the second channel bend *f* is of rectangular or other suitable cross-section same as the fore chamber *c* and the slot *e*.

A connecting part *g* extends from the second bend *f* to the reduced portion *h*.

In order to better depict the whole of the discharge channel from the pan *a* to the discharge pipe *i* the dimensions are given below. The fore chamber *c* for example has a cross-section of about 100 x 55 mms., the slot *c* and the siphon channel *b* connected therewith have the same dimensions up to the sec-

ond bend *f*. The upright tapered portion *g* extending from the second bend *f* measures about 80 mms. at the top and about 95 mms. at the bottom and the reduced portion is about 57 mms. in diameter. The discharge pipe and the connecting part *i* have the standard diameter of 95 mms.

As the slot *e* is perpendicular to the fore chamber *c* only fecals up to 55 mms. in diameter can pass into the channel *b* or only such as are smaller than the diameter of the reduced portion *h*. Consequently there is no danger of stoppage occurring in the discharge channel.

This construction enables the cross-section at the entrance to be sufficiently large for the suction effect.

I claim:—

A water closet pan, comprising a fore chamber of rectangular cross-section arranged between the pan and the siphon channel and having a slot extending through the bottom and wall perpendicular to said fore chamber and of the same cross-section as said fore chamber.

In testimony whereof I affix my signature.

MAX HOLLENWEGER.
